UNITED STATES PATENT OFFICE

131,473

DESIGN FOR A COMBINATION STORAGE CABINET, MAGAZINE RACK, AND SEAT

Clement C. J. Thelander, Chicago, Ill., assignor of one-half to Andrew F. Wintercorn, Rockford, Ill.

Application July 18, 1941, Serial No. 102,217

Term of patent 14 years

To all whom it may concern:

Be it known that I, Clement C. J. Thelander, a citizen of the United States, residing at Chicago, in the county of Cook and State of Illinois, have invented a new, original, and ornamental Design for a Combination Storage Cabinet, Magazine Rack, and Seat, of which the following is a specification, reference being had to the accompanying drawing, forming part thereof.

In the drawing:

Fig. 1 is a perspective view of the combination storage cabinet, magazine rack, and seat embodying the design of my invention, and

Fig. 2 is another perspective view looking at the article from the opposite end and showing the seat raised for access to the storage compartment.

I claim:

The ornamental design for a combination storage cabinet, magazine rack, and seat, substantially as shown.

CLEMENT C. J. THELANDER.
